COMBINED BATTERY OPERATED MASSAGER HANDLE AND RECHARGING STAND

Edward A. Irelan, Lombard, Ill., assignor to Sunbeam Corporation, Chicago, Ill., a corporation of Illinois

Filed July 1, 1968, Ser. No. 12,564

Term of patent 14 years

Int. Cl. D4—02

U.S. Cl. D4—19

FIG. 1 is a front perspective view of a battery operated massage handle with recharging stand embodying my new design;

FIG. 2 is a side elevational view thereof;

FIG. 3 is a rear elevational view thereof; and

FIG. 4 is a top plan view thereof.

The massaging brush shown in broken lines in FIG. 1 is for illustrative purposes only and form no part of the claim.

I claim:

The ornamental design for a combined battery operated massager handle and recharging stand, as shown and described.
